UNITED STATES PATENT OFFICE

2,421,289

ABRASIVE BELT MACHINE

Lewis Roth, Du Bois, and John M. Schnaus,
Jasper, Ind.

Application December 27, 1944, Serial No. 570,490

5 Claims. (Cl. 51—141)

1

Our invention relates to abrasive machines.

It is a main object of our invention to provide in an abrasive machine employing an abrasive band traveling at high speed a spring suspended sand belt forming block for forcing the belt into contact with the edge face of wood or similar material after it has been operated upon by an edge tool or tools whereby it is expeditiously smoothed and brought to shape and/or size and has special reference to effecting the final finish on curved, irregular or molded edge faces of material.

Another main object of this invention resides in providing a frictionless mounting for the sanding block referred to in the preceding paragraph.

Another object of this invention resides in providing a mounting for a sanding block wherein the latter will remain in balance at all times, that is, whether idle or at work and subjected to pressures ranging from light to heavy work thereby simulating the action of a human hand under the guidance of a highly trained skilled operator.

Still another object of this invention resides in providing a suspension for a sanding block of the type specified above wherein the weight of said block is yieldingly suspended at all times thereby preventing the weight of the block from resting on the stock under treatment.

Other objects and advantages will be manifest as the description of this invention progresses.

In the accompanying drawings selected for disclosing an embodiment of our invention:

Figure 1 is a perspective view of our sanding block and the mounting therefor reproduced from a photograph of a full size device that has been in use finishing edge faces and moldings for commerce. The structure shown in this figure is designated as and referred to hereinafter sometimes as "unit A".

Figure 2 is a front end elevation of Figure 1.

Figure 3 is a plan view showing a typical abrading machine equipped with our improved sanding unit on a reduced scale from that employed in Figures 1 and 2.

Figure 4 is a vertical section elevation of Figure 3 along line 4, 4, without the sanding belt, auxiliary idler therefor or the elements in the background thereof.

Numeral 5 designates a sanding block that is pivotally mounted on arm 6 depending from flat spring 7 by means of pivot shaft 8 journaled in the block. The arm is shown astride and preferably riveted to the spring adjacent the free end 7A thereof. Obviously, a pivot mounting can be substituted for the rivet attachment. The lower

2

ends of auxiliary aligning springs 9—9 are attached to block 5 and the upper ends to bolts 10, 10 that pass through spring 7 freely and carry wing nuts 11, 11. The lower end 7B of spring 7 is provided with slot 7C that registers with slot 12A in base plate 12 in order that bolt 13 can pass through yoke 14 and said slots when the complete sanding unit A is to be attached to the top of the abrasive machine shown in Figures 3 and 4. The function of bolts 16, 16 and the wing nuts 16A at the top end thereof is to set the free end of the flat spring in terms of base plate 12 to which the lower ends of said bolts are anchored as best shown in Figure 1. It will be observed that free end 7A of the flat spring and arm 6 depending therefrom will be raised or lowered in response to corresponding manipulation of wing nuts 16A thereby raising or lowering block 5, through micrometer adjustments, an important feature that contributes to the main objectives of the structure constituting unit A. It will be pointed out more in detail hereafter as to the utility of raising and lowering the face 5A of block 5.

Numeral 17 designates a frame or table having at one end a vertical spindle 18, supported in suitable bearings and rotated by belt 19, running on pulley 20 from drive pulley 21, which in turn is mounted on horizontal shaft 22, driven by power from any convenient source. The upper end of spindle 18 carries a large horizontal pulley or drum 23 fixed thereon, and at the opposite end of the table is a similar pulley 24 mounted on short shaft 25 so as to revolve freely thereon.

Numeral 26 designates an endless belt or band of webbing coated on the outer face with an abrasive of the desired fineness embedded in glue, according to well understood practice. The band should be of a length sufficient to form a belt

running snugly upon pulleys 23 and 24, and in order to take up any slack resulting from the usual causes, the short shaft 25 is preferably mounted on slide 28, carried in ways 29 on the table and adjusted longitudinally of the latter by screw 30. Numerals 27, 27 indicate conventional idlers or guide members for directing the band from the normal line extending from drum 23, face 5A and drum 24. For processing certain objects, such as irregular edge faces of table tops

or the like, the belt must be directed from said normal line to prevent contact between same at points other than at face 5A.

At about the mid-length of the table top 15 and within the band, unit A is mounted so that face 5A of sanding block 5 will be in alignment

with the back or un-sanded side of the abrasive belt and so that the upper edge will extend into slot 5B, as shown in Figures 1 and 4. Numeral 5C designates a metallic insert, preferably type metal, that can be readily removed and restored to form a matrix from a patrinx improvised by properly coating the face of the molding ready for sanding.

Special attention is directed to pivot shaft 8 having its true axis substantially coincident with a horizontal plane passing through the working center of sanding belt 26 and that by this arrangement working face 5A of block 5 and/or said block can be equally disposed on each vertical side thereof. Obviously, this feature contributes to the balancing of pressures adverted to at the outset hereof. It should also be noted in Figure 3 that even if idlers 21, 27 were omitted the near section of said belt 26 would be forced out of a vertical plane or straight travel from the near faces of pulleys 23-24 by face 5A so that said belt will be strained outwardly when an edge face or molding is pressed against the area of the sand belt traveling rapidly over face 5A said belt will be forced to conform to the abutting exterior, thereby effecting a final finish, in a single operation, of the applied edge face or molding.

Numeral 31 is a folding leaf mounted in frame 32 supported in vertical ways 33 on the main frame 17 and adjustable vertically by screw 37 and hand wheel 36 keyed thereto according to accepted practice. Leaf 31 is so set for working that its upper edge projects above the edge of table top 15 in front of face 5A and functions as a convenient support for the articles under treatment. This leaf 31 is hinged to the frame at the top and the angle of said leaf 31 may be varied as required by releasing screw 35 impinging against the side of segmental arm 38, as indicated in the drawings and elevating or lowering the free end of the leaf until the desired inclination of the top face thereof is attained after which screw 35 is tightened.

By the means set forth above, it will be understood that the objects adverted to at the outset of this specification can be accomplished easily, expeditiously and uniformly. It will also be understood that modifications can be made without departing from the spirit of this invention, consequently we wish to be limited only by the claims appearing herein.

We claim:

1. In apparatus for sanding edge faces or the like comprising a table, a leaf spring of substantially C formation having one end secured to the top of said table, a sanding block suspended from the free end of said spring by a rigid arm pivotally attached to said block for free movement, said block having a face conforming to the edge faces to be finished and a sanding belt disposed so that the edges thereof will be substantially parallel to the top of said table; means for driving said belt, the belt being trained over the face of said block.

2. In apparatus for sanding edge faces or the like comprising a table, a sanding block, a main spring means operatively mounted in relation to

said table for entirely suspending said block, said block having a face conforming to the edge face to be finished; a sanding belt operatively associated with said block; means for driving said belt, the belt being trained over the face of said block, means for adjusting said spring and a pair of auxiliary springs attached to said main spring and said block for balancing the block and locating the face thereof.

10 3. In apparatus for sanding edge faces or the like comprising a table, a main spring mounted on said table, a sanding block mounted on said spring, auxiliary spring means connected at one end to the main spring and at the other end to the block, said block having a face conforming to the edge faces to be finished; a sanding belt disposed so that the edges thereof will be substantially parallel to the top of said table; means for driving said belt, the belt being trained over the face of said block, said block being suspended entirely from said main spring and balanced by said auxiliary springs, each of said springs being provided with individual means for varying respectively the tension thereof.

15 4. In an apparatus for sanding the edge faces of boards or the like comprising a table, a leaf spring, said spring having one end secured to the top of said table, an arm depending from the free end of said spring, a sanding block having a face for engagement with an abrasive medium, said sanding block being oscillatively suspended from the free end of said spring with an axis of said block retained in spaced-fixed relation to said free end, and yielding means cooperating with 20 said free end and said block to provide free movement thereof in response to force applied thereto through the abrasive medium to said face.

25 5. In apparatus for sanding edge faces or the like comprising a table, a main spring mounted on said table, a sanding block mounted on said spring, auxiliary spring means connected at one end to the main spring and at the other end to the block, said block having a face conforming to the edge faces to be finished; a sanding belt disposed so that the edges thereof will be substantially parallel to the top of said table; means for driving said belt, the belt being trained over the face of said block, said block being suspended entirely from said main spring and balanced by 30 said auxiliary springs.

LOUIS ROTH,
JOHN M. SCHNAUS.
